UNITED STATES PATENT OFFICE.

AUGUST C. RADER, OF UPPER MONTCLAIR, NEW JERSEY.

CAR-SEAT.

1,142,203.

Specification of Letters Patent.

Patented June 8, 1915.

Application filed November 4, 1912. Serial No. 729,508.

To all whom it may concern:

Be it known that I, AUGUST C. RADER, a citizen of the United States, residing at Upper Montclair, in the county of Essex and State of New Jersey, have invented a new and useful Car-Seat, of which the following is a specification.

This invention relates to car seats, and more particularly to that type of car seat in which the back is shiftable relative to the seat so as to render the seat quickly reversible.

One of the objects of the invention is to provide means whereby the back can be readily shifted from one position to the other, there being rollers for supporting the back during its movement, and these rollers likewise serving as means for holding the back in either of the two positions to which it may be shifted.

Another object is to provide means whereby the rollers can be readily shifted out of either of the positions occupied thereby while holding the back in inclined or active position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings: Figure 1 is a side elevation of a seat having the present improvements combined therewith. Fig. 2 is a transverse section therethrough, said section being taken on the line A—B Fig. 1, the seat, proper, being elevated, and a portion of the back being shown in section. Fig. 3 is a perspective view of a portion of the seat support and showing the channel for the reception of the supporting rollers of the back. Fig. 4 is a perspective view of one of the side hangers of the seat back and showing the carriage and lifting device thereon. Fig. 5 is a side elevation of a portion of said hanger and carriage, the lifting device being shown. Fig. 6 is a view showing, in detail, one of the side thrust bearings. Fig. 7 is a section through a modified form of supporting

roller. Fig. 8 is an enlarged section through the upper portion of the seat back and the garment hanger carried thereby.

Referring to the figures by characters of reference 1 designates the seat supports the same constituting the sides of the seat and each being preferably formed in a single casting. Each of these supports is provided, in its inner surface and adjacent the upper edge thereof with a longitudinal channel 2, the bottom wall of the channel constituting a guide. Recesses 3 are formed at the ends of the bottom wall of each channel and projecting upward from said wall or guide near the recesses and adjacent the outer edge of the wall are projections 4 for the purpose hereinafter set forth.

The seat-back, which has been indicated at 5, is provided, at its sides, with parallel hangers 6, these hangers extending downwardly between the supports 1. Secured to each hanger 6 is a carriage 7 made up of a frame having cross rods 8 on which are mounted antifriction rollers 9. These rollers are arranged in pairs and are preferably shaped as shown in figures 2 and 4, the rollers being of greater diameter at their centers than at their ends. A lifting finger 10 is pivotally connected to each hanger 6 and hangs freely between the rollers 9 on the hanger, this finger projecting downwardly below the rollers. If desired, stop lugs 11 may be arranged on each hanger 6 at opposite sides of the finger 10 so as to limit the swinging movement of the finger.

Secured to each of the hangers 6 at points below the carriage 7 thereon are side thrust devices each of which preferably consists of a ring-like casing 12 having a series of antifriction balls 13 therein and upon which bears a single ball 14 which is held against displacement by the housing 12 and bears against the inner side of the adjacent support 1. Any desired number of these side thrust bearings may be used, two being shown in the present instance applied to each hanger 6.

Instead of utilizing solid rollers 9 such as shown in Fig. 4, the rollers employed may be provided with conical recesses 15 extending thereinto from the ends thereof so as to form a throat 16 at the center of the roller. A small knob 17 carried by the pivot pin 18 may be forced into the throat 16 which throat can be provided with a shallow annu-

- lar groove for the reception of the knob. Closure plates 19 may be seated in the outer end portion of the recesses 15 so as to hold the rollers against rocking on the pins 18.
- 5 The hangers 6 extend downwardly sufficient distances to project between links 20 which, as shown in Fig. 1, are provided with longitudinal slots 21 and are pivotally supported by a rod 22. This rod 22 is upheld by brackets 23 extending downwardly under the seat 24. The slots 21 receive studs 25 extending laterally from the lower end portions of the hangers 6. The lower ends of the links 20 are connected by a bar 26 constituting a foot rest.
- 10 It is to be understood that when the seat-back is in use, one of the rollers 9 rests within one of the recesses 3 and the lifting finger 10 bears downwardly upon the lower wall of the channel 2 and directly back of and in contact with one of the projections 4. When it is desired to shift the seat-back to its other position the upper end of the seat-back is pushed toward the opposite side of the seat and, as the lower end of the finger 10 is held against movement longitudinally of channel 2 by the projection 4, it will be obvious that this movement will result in the finger swinging about its lower end as a pivot. This obviously will result in the elevation, bodily, of the seat back and lifting the seated roller 9 out of the recess 3 in which it is mounted. As soon as the finger 10 has reached a vertical position, the two rollers 9 will be brought above the bottom wall of the channel 2 and are thus free to travel therealong, the seat back 5 being held vertically during this traveling. The projections 4 are located at one side of the path of the rollers and will not, therefore, interfere with their movement. As the seat back moves from one end to the other of the supports 1, the studs 25 work within the slots 21 and cause the links 20 to swing downwardly under the brackets 23 and then upwardly to their new positions, thus reversing the position of the foot rest 26. As the seat back reaches the limit of its movement, one of the rollers 9 on each carriage drops into the adjacent recess 3, thus causing the seat back to assume an inclined position. At the same time, the finger 10 drops into position back of and close to the adjacent projection 4. It will be apparent that by utilizing this lifting finger the operation of disengaging the rollers 9 from the recesses 3 is rendered less laborious than would be the case should it be necessary to force the roller out of the recess by pushing upwardly on the back and then shifting the same to its new position.
- 15 If desired, and as shown in Figs. 1, 2 and 8, the back may be provided with a garment hanger. This hanger includes a rod 27 having its ends bent so as to lie close to the sides of the back while the rod is extended along

the upper edge of the back. The ends of the rod are pivotally connected to the back, as shown at 28. A recess 29 extends downwardly into the back from the center of the upper edge thereof and mounted in the upper edge 70 of the back at opposite sides of the recess 29 are guide sheaves 30. An adjusting screw 31 is mounted in the lower portion of the recess 29 and has a coiled spring 32 attached to it, this spring extending upwardly within recess 29. A chain 33 or any other suitable flexible connection extends from the upper end of the spring and between the guide sheaves and is secured at its outer end to the bar 27. Thus it will be seen that bar 27 can 75 be swung to position beyond either side of the back 5 and, when not in use, the spring 32 serves to hold the bar upon the top of the back where it will practically close the upper end of the recess 29. The rod 27 may be 80 provided with a knob 34 whereby it can be swung easily to active position so as to support a coat or other garment back of the seat. It is to be understood of course that a pair of rollers 9 and a single lifting finger 90 90 are to be provided at each side of the back so as to coöperate with the respective supports 1. It is to be noted that the term "guide," as used in the claims, applies to the lower or bottom wall of the channel 2. 95 In order that the seat 24 may be tiltably mounted between the supports, cross bars 35 connect the front and back portions of the supports 1 and have bowed supporting rails 36 attached thereto, the seat being adapted 100 to rock upon these rails. Each hanger has a pair of tilting rollers 37 extending inwardly therefrom and these rollers travel over flanges 38 outstanding from the lower edges of the sides of the seat. Thus it will 105 be seen that when the seat back is shifted to one position, one of the rollers 37 will push downwardly on flange 38 and tilt the seat in one direction and, when the back is moved to its other position, the other roller 37 will press downwardly on flange 38 and thus tilt the seat to its other position. The brackets 23 are secured to and extend downwardly 110 from the bowed rails 36.

What is claimed is:—

1. The combination with a seat support having a guide formed with terminal recesses, of a seat-back, means movable therewith for becoming seated in the respective recesses to hold the back in active position, and means coöperating with said guide for elevating the seated means out of its recess when the back is shifted out of active position.

2. The combination with a seat support 125 having a guide formed with a recess in its lower surface, of a seat-back, a roller movable therewith and adapted to be seated in the recess to hold the back in active position, and coöperating means upon the guide and 130

upon the seat-back respectively, for elevating the roller out of the recess when the back is shifted out of active position.

3. The combination with a seat support having a guide channel and recesses in the bottom of the channel, of a seat-back, rollers movable with the back and adapted to be seated in the respective recesses to hold the back in either of two active positions, and means movable with the seat back and co-operating with the bottom of the guide channel in which the rollers are mounted for elevating either roller out of the recess in which it is seated during the initial movement of the seat-back out of either active position.

4. The combination with a seat support having a channeled guide provided with terminal recesses, of a movable seat-back, a hanger depending therefrom, rollers in fixed relation to and movable with the hanger and adapted to travel along the bottom of the guide channel to hold the seat back in up-standing position and to become seated in the respective recesses to hold the back in an inclined position, and co-operating means upon the hanger and upon the bottom of the guide in which the rollers are mounted, for elevating the back and rollers to disengage the seated roller from the recessed portion of the channel.

5. The combination with a seat support having a channeled guide provided with terminal recesses, of a movable seat-back, rollers movable with the back and disposed in fixed relation thereto, said rollers being adapted to be seated within the respective recesses to hold the back in either of two

active positions, a finger pivotally mounted and movable with the back, and projections upon the bottom of the channeled guide and adapted to be engaged by the finger to bodily elevate the back and rollers when the back is moved relative to the support.

6. The combination with a seat support having a guide formed with terminal recesses, of a seat back, rollers movable therewith for becoming seated in the respective recesses to hold the back in active position, a projection adjacent each recess and extending from the guide, and a lifting element pivotally connected to the back and movable against the projections for elevating the rollers out of the respective recesses when the seat back is shifted.

7. The combination with a seat support having a guide channel and recesses in the bottom of the channel, of a seat back, means movable with the back and adapted to be seated within the respective recesses to hold the back in either of two active positions, and means pivotally connected to and movable with the seat back and co-operating with the support for elevating each of said first named means out of the recess in which it is seated during the initial movement of the seat back out of either active position, said pivoted means being constantly housed within the channel.

In testimony that I claim the foregoing as my own, I have hereto affixed my signature in the presence of two witnesses.

AUGUST C. RADER.
